UNITED STATES PATENT OFFICE.

JAMES BROWN PRICE, OF CROSS KEYS, ENGLAND, ASSIGNOR OF ONE-HALF TO LUTHER SILVERTHORNE, OF NEWPORT, ENGLAND.

DOUBLE-ACTING INTERNAL-COMBUSTION ENGINE.

Application filed February 7, 1920. Serial No. 356,952.

To all whom it may concern:

Be it known that I, JAMES BROWN PRICE, a subject of the King of Great Britain and Ireland, and a resident of Cross Keys, county 5 of Monmouth, England, have invented a certain new and useful Improvement in Double-Acting Internal-Combustion Engines, of which the following is a specification.

10 This invention relates to an improvement in internal combustion engines.

More particularly the invention relates to double acting internal combustion engines of the type wherein the charge is admitted 15 into and given a preliminary compression in one chamber, and then transferred into a second chamber where it replaces the exhaust gases therein, and is compressed and fired. That is to say the invention relates to engines of the character set forth comprising 20 a fixed piston secured within the working cylinder, and a hollow working piston arranged to surround the fixed piston and located between the same and the inner wall 25 of the working cylinder in such a manner that it may freely reciprocate with reference to the fixed piston.

One of the objects of the invention is to provide a more powerful and less complicated engine of the type set forth, thereby 30 particularly adapting it for use on motor cars, motorcycles, airplanes and the like.

With the above and other objects in view which will more readily appear as the nature 35 of the invention is better understood, the same consists in the novel construction, combination and arrangement of parts herein-after more fully described, illustrated and claimed.

40 A preferred and practical embodiment of the invention is shown in the accompanying drawings in which:

Figures 1 and 2 are vertical sectional views taken at right angles to each other.

45 Similar reference numerals designate corresponding parts throughout the several figures of the drawings.

In a double acting engine constructed in accordance with this invention two working 50 chambers are employed constituted by a fixed piston arranged centrally in the cylinder, and each chamber is provided with a piston, said piston being operatively connected by a suitably perforated cylindrical wall, and 55 each serving to highly compress a charge of

fuel and transfer such initially highly compressed charge from one side of the piston in one chamber to the other side of the piston in same chamber where it is further highly compressed and fired.

60 Referring to Figures 1 and 2, the working pistons 10, 11 are constituted by the ends of a hollow piston 1 reciprocating within the cylinder 2 and connected by means of a sleeve piston rod 3 with a cross head 4 that is coupled by a pair of connecting rods 5 with the cranks 6 of the crank shaft 7. Within the hollow piston 1 is the fixed piston 8 on a rod 9 on which runs the sleeve 3 and which is carried by a bracket B bolted to the engine 70 framework. The further essential parts are indicated in the following description of the action of the engine.

75 The upper working piston 10 commences its down stroke, the lower one 11 drawing away from the fixed piston 8 thus creating a partial vacuum between itself and the fixed piston. This causes gas to be drawn through the lower valve 14 and the holes 17 in the wall of the double piston until the lower 80 piston reaches the bottom of its stroke when said valve 14 closes. The lower part 12 of the valve box, the inlet ports and the space between the lower piston 11 and the fixed 85 piston 8 are now full of gas and the up stroke commences compressing this gas until the bottom edge of the lower piston 11 reaches the lower edge of the port 12 inside the lower valve 14, when gas is transferred through the holes 17 in the piston wall then 90 through said inlet port 12 and thus into the lower combustion chamber where it may be suitably deflected from the exhaust ports 18, while the exhaust gases are driven through the latter. A deflector 13 is shown on the 95 piston. While this is taking place the space between the upper piston 10 and the fixed piston 8 has filled with gas in a similar manner to the lower space on the down stroke.

On the next down stroke the gas is compressed and fired in the usual manner in the lower combustion chamber, the upstroke doing the same for the top combustion chamber. The exhaust is similar to "two strokes" practice.

105

I claim:

1. A double-acting internal combustion engine of the class described including a main cylinder, a fixed piston therein, a reciprocating double piston having the side 110

wall thereof perforated for transferring a compressed charge from one side of one of the pistons to the opposite side, the said compressed charge being passed into the working chamber of the same portion of the main cylinder where initial compression occurred.

2. A double-acting internal combustion engine of the class described including a main cylinder, a fixed piston, fuel inlet valves arranged at opposite sides of the fixed piston, a hollow working piston presenting opposite piston heads and working over the fixed piston and providing interior initial compression chambers alternately at each side of the latter, said working piston having perforations in its side wall to allow of admission of fuel from one of the inlet valves into one of the initial compression chambers during the admission stroke of the piston and whereby upon the admission stroke of the opposite piston head the charge contained within the initial compression chamber of the hollow piston will be forced therefrom through the perforations into the adjacent working chamber of the main cylinder.

3. A double-acting internal combustion engine of the class described including a main cylinder, having paired inlet and exhaust ports arranged centrally thereof, a fixed piston arranged between the paired inlet and exhaust ports, a hollow working piston slideable in the main cylinder and adapted to alternately cover and uncover the exhaust ports and having perforations arranged on the side adjacent the inlet ports whereby upon the movement of the hollow working piston in opposite directions fuel will be drawn alternately into the space between the ends of the hollow piston and the op-

posite sides of the fixed piston and then alternately compressed upon the closing of the inlet ports into the working chambers of the main cylinder.

4. An internal combustion engine, including a cylinder having intake and exhaust ports, a standard supported in the crank case of the engine and projecting into the cylinder, a piston carried by the end of the standard and arranged in a fixed position between the intake and exhaust ports, a hollow piston having perforations in its side wall and adapted to operate between the periphery of the said fixed piston and the interior of the cylinder, said hollow piston having closed end walls, a sleeve carried by one of said end walls and slidably mounted on said standard, and crank connections with one end of said sleeve.

5. An internal combustion engine including a cylinder, a standard arranged axially of the cylinder and projecting externally thereof, means for rigidly securing the end of the standard projecting externally of the cylinder to the crank case, a stationary piston head arranged at the intermediate part of said cylinder, and a hollow piston having perforations in its side wall and having opposite closed end walls, and means connected with one of the closed end walls of the hollow piston for reciprocating the same with reference to the stationary piston, and said means being concentric with the standard for supporting the said stationary piston head.

In testimony whereof I have affixed my signature hereto this 26th day of December, 1919.

JAMES BROWN PRICE.
